UNITED STATES PATENT OFFICE

LANCASTER P. CLARK, JR., OF SOUTH NORWALK, CONNECTICUT

DESIGN FOR AN ELECTRICAL PLUG DEVICE

Application filed November 19, 1931. Serial No. 41,783. Term of patent 7 years.

To all whom it may concern:

Be it known that I, LANCASTER P. CLARK, Jr., a citizen of the United States, residing at South Norwalk, in the county of Fairfield and State of Connecticut, have invented a new, original, and ornamental Design for Electrical Plug Device, of which the following is a specification, reference being had to the accompanying drawings, forming part thereof.

In the drawings:

Fig. 1 is a side elevation of an electrical

plug device, showing my new design, the prongs being shown in dotted lines.

Fig. 2 is a front elevation; and

Fig. 3 is a bottom plan view.

I claim:—

The ornamental design for an electrical plug device, as shown.

Signed at Bridgeport, in the county of Fairfield, and State of Connecticut, this 6th day of November, 1931.
